(57) **CLAIM**

The ornamental design for a garment, as shown and described.

DESCRIPTION

FIG. 1 is a rear perspective view of a garment showing my new design;

FIG. 2 is a rear view thereof;

FIG. 3 is a side view thereof;

FIG. 4 is a second side view thereof;

FIG. 5 is a front view thereof; and,

FIG. 6 is a top view thereof.

The long and short broken lines are unclaimed boundaries of the claimed design. It is understood that the claimed design extends to these boundaries but does not include the boundaries.

The even-length broken lines shown in the drawings are directed to environment and form no part of the claimed design.
